UNITED STATES PATENT OFFICE.

CHARLES A. BABCOCK, OF BUFFALO, NEW YORK, ASSIGNOR TO PRATT & LETCHWORTH, OF SAME PLACE.

DESIGN FOR A CARRIAGE-STEP.

SPECIFICATION forming part of Design No. 15,759, dated February 3, 1885.

Application filed December 31, 1884. Term of patent 7 years.

To all whom it may concern:

Be it known that I, CHARLES A. BABCOCK, a citizen of the United States, residing at Buffalo, in the county of Erie and State of New York, have invented and produced a new and original Design for Carriage-Steps, of which the following is a specification.

This design relates to the ornamentation of the upper surface of a carriage-step by means of ornamental ribs; and it consists of the special features which will be hereinafter described and claimed, and which are represented in the accompanying drawing, which represents a top plan view of the carriage-step.

A represents the plate of the carriage-step, which is square or rectangular in form, and provided with a marginal rib or bead, a.

O represents a square or rectangular rib or bead on the plate A, parallel with the four sides thereof.

D represents pointed arches extending from the corners of the inner rib, C, to the corners of the plate, and d are similar pointed arches, made smaller in size and extending from the

sides of the inner rib, C, to the sides of the plate A.

E represents four groups of parallel ribs extending from the four corners of the inner rib, C, inwardly to two crescent-shaped ribs, e.

F represents a central ornament grouped centrally on the plate A between the ribs e, and composed of pointed ornaments extending radially around a central concave depression, f.

g g are openings formed in the plate A.

I claim—

The design for a carriage-step, consisting of an inner field provided with a central ornament, F, and surrounding groups of parallel ribs E, and arches D d, extending from the inner field outwardly, substantially as shown and described.

Witness my hand this 19th day of November, 1884.

CHAS. A. BABCOCK.
